(57) CLAIM

The ornamental design for a plant pot holder for wall hung display, as shown and described.

DESCRIPTION

FIG. 1 is a perspective view of a plant pot holder for wall hung display according to the present invention.

FIG. 2 is a front elevation view of the plant pot holder for wall hung display illustrated in FIG. 1.

FIG. 3 is a rear elevation view of the plant pot holder for wall hung display illustrated in FIG. 1.

FIG. 4 is a top plan view of the plant pot holder for wall hung display illustrated in FIG. 1.

FIG. 5 is a bottom plan view of the plant pot holder for wall hung display illustrated in FIG. 1.

FIG. 6 is a side elevation view of the plant pot holder for wall hung display illustrated in FIG. 1; and,

FIG. 7 is another side elevation view of the plant pot holder for wall hung display illustrated in FIG. 1.

The broken lines in the drawing depict environmental subject matter only and form no part of the claimed design.
